UNITED STATES PATENT OFFICE.

JOHN M. LOVAAS, OF MINNEAPOLIS, MINNESOTA.

FLASH-LIGHT TRAFFIC SIGNAL.

Application filed May 11, 1923. Serial No. 638,260.

To all whom it may concern:

Be it known that I, JOHN M. LOVAAS, a citizen of the United States, residing at Minneapolis, in the county of Hennepin and 5 State of Minnesota, have invented certain new and useful Improvements in Flash-Light Traffic Signals; and I do hereby declare the following to be a full, clear, and exact description of the invention, such as 10 will enable others skilled in the art to which it appertains to make and use the same.

My invention provides an extremely simple and highly efficient direction signal for use by drivers of automobiles or other motor-propelled vehicles, and to such ends, generally stated, the invention consists of the novel devices and combinations of devices hereinafter described and defined in the 15 claim.

20 The signal device is adapted to be worn on or applied to the wrist of the driver, much like a wrist watch, and it involves the use of a small electric light bulb and suitable energizing circuit, which circuit includes an automatic gravity-operated 25 circuit-controlling switch, which, when the hand to which the device is applied, is used in the ordinary way to steer a machine or perform the ordinary operations in the control of the machine, will open the circuit and 30 cut the light bulb out of action, but which, when the hand is thrown outward and turned thumb down, which is a natural position, will cause the circuit to be closed and 35 the light bulb to be illuminated.

In the accompanying drawings, which illustrate the invention, like characters indicate like parts throughout the several views.

Referring to the drawings:

40 Fig. 1 is a fragmentary perspective illustrating the use of the signal device applied to the wrist of the driver of an automobile;

Fig. 2 is a transverse section taken through the signal device on the irregular line x^2 —

45 x^2 of Fig. 3;

Fig. 3 is a front elevation of the device with the case thereof sectioned approximately on the line 3—3 of Fig. 2;

Fig. 4 is a section on the line 4—4 of Fig.

50 2, some parts being shown in full;

Fig. 5 is a perspective showing the storage battery of the device;

Fig. 6 is a diagrammatic view with some parts shown in full section, illustrating the

lamp circuit and circuit-controlling switch; 55

Fig. 7 is a side elevation illustrating a modified form of the signal device; and

Fig. 8 is a perspective of the device shown in Fig. 7.

In the arrangement illustrated in Figs. 1 to 6, inclusive, the numeral 9 indicates a small metallic casing made much like the casing of a "vest pocket" flashlight, except that it has a laterally extended chamber 10 to receive and detachably hold a small reflector 11. Within the main chamber of the casing 9 is inserted a small battery 12, such as used in flashlights of the type just noted.

The reflector 11, which is of metal and, hence, an electrical conductor, is provided 70 with a small light bulb 13 detachably held thereby in the customary way with its sleeve-like outer contact electrically connected to the reflector 11 and with its axial electrode 14 normally engaged with an insulated T-shaped bus bar 15. This bus bar 15 extends from the reflector receiving chamber 10 into the battery-containing compartment, but is insulated from all of the metallic parts of the casing. The battery 12 has the two 80 customary terminal contacts 16 and 17, the former of which, when the battery is in position, is yieldingly pressed into electrical contact with the bus bar 15. The terminal contact 17 normally stands just out of engagement with the adjacent end of a metallic guide tube 18 that is secured within the casing immediately adjacent to one side of the battery. Working freely within the 85 guide tube 18 is a sliding circuit-controlling contact 19, preferably made in the form of a small plunger or rod section. Working through the one end of the casing is a push button 20 preferably of insulating material 90 and the headed inner end of which lies normally nearly or in engagement with the terminal contact 17.

At one side, the casing 9 is concavely curved and, at its extremities, is provided with slotted lugs or projections 21. At 100 said concave side, the casing is normally closed by a concave side plate 22 that is detachably held in position by friction or any other suitable means, and which, when removed, affords ready access to the battery 105 and to the light font and enables both to be removed and replaced.

To hold the signal device on the wrist of

the operator, I preferably employ a wrist strap 23 which is passed through the slot lugs 21 and is equipped with a buckle 24, whereby the signal device may be applied to the wrist as clearly shown in Fig. 1.

Fig. 6 does not show the bus bar 15, but the wiring is there diagrammatically indicated, and it will be obvious, by following either this diagram or the actual structure described, that when the signal device is turned upside down, as shown in Fig. 3, the plunger 19 will drop into engagement with the terminal contact 17 and will close the battery circuit through the light bulb 13; and, on the other hand, when the battery is turned right side up or reversed from the position shown in Fig. 3, the plunger 19 will slide into the tube 18 out of engagement with the contact 17, thereby opening the battery circuit and cutting the light bulb out of action, which is the normal condition or condition existing at all times except when, for example, the operator throws his hand outward and reverses the hand and signal device substantially as shown in Fig. 1. Thus, it will be understood that the signal device, when applied to the wrist, will be automatically operated without requiring the operator to give the same any attention whatever other than to give the natural signal almost universally used and which consists in throwing out the hand. When the hand is thrown out and the light bulb temporarily illuminated, a very distinct signal will be given to a machine in the rear, even on a dark night.

The modified arrangement of the device illustrated in Figs. 7 and 8 differs from that already described in that the battery and circuit-controlling switch will be placed in a small casing 9^a and the light font, including the electric bulb, will be placed in a light font casing 10^a. In this arrangement, the casing 9^a is provided with perforated ears 21^a through which a strap 23^a is passed, and the concave removable plate 22^a is secured to said strap by rivets 25 or other suitable means. The light font casing 10^a is secured on the strap at a point distant from the casing 9^a and the battery is connected

to the light bulb through wires or circuit connections 15^a in which the automatic switch, not shown, is applied.

In the arrangement shown in Figs. 7 and 8, the casings 9^a and 10^a are so spaced that they will be on opposite sides of the wearer's wrist.

If at any time it should be desirable to use the device above described as a flashlight, the circuit can be closed simply by pressing on the push button 20 so as to force the terminal contact 17 against the adjacent end of the metallic guide tube 18.

From what has been said, it will be understood that the invention is capable of modification and that the general arrangement described, with any kind of a gravity-operated switch, would be within the broad scope of the invention. Nevertheless, more important details are herein involved.

What I claim is:

1. A direction signal comprising a casing, and an electric circuit in the casing including a light bulb, a battery, a tube grounded through the casing, and a gravity-operated sliding plunger in the tube, said battery having a yielding terminal contact normally out of engagement with the tube and in position to make contact with the end of the sliding plunger only when the signal is held in signaling position, and a non-conducting push button in position for moving the said yielding terminal contact into engagement with the end of the tube.

2. A direction signal comprising a casing, and an electric circuit in said casing including a light bulb, a battery, a tube grounded through the casing, and a gravity-operated sliding plunger in said tube, said battery having a terminal contact normally out of engagement with said tube and in position to make contact with the end of said sliding plunger only when the signal is held in signalling position, and a non-conducting button operative to move one of the circuit-forming elements and close said circuit, at will and irrespective of the position of said signalling device.

In testimony whereof I affix my signature.
JOHN M. LOVAAS.
